OPPOSITELY SWINGABLE LIGHT STRUCTURE

James H. Reichart, Muncie, Ind.

Application January 12, 1944, Serial No. 517,909

15 Claims. (Cl. 240—2)

1

This invention relates to a lamp structure and containing accessory mountings for a stove, such as of electrical, gas, gasoline, kerosene or the like, but which is accessible to a source of electrical energy.

Certain portions of the invention, however, are not necessarily restricted to stove use or application.

In regard to stove use, one of the chief objects of this invention is to provide a source of illumination for a stove, the illuminating means being so carried by the stove that said means may be swung forwardly and thus direct illumination downwardly upon the top face of the stove and into the vessels thereon.

Another object of the invention is that when the hinge axis of such illuminating means is inclined to the top surface of the stove, the outer end of the swung illuminating means is elevated above the normal elevation of said end when in unswung position.

Another object of this invention is to supply electrical energy for illumination purposes through a hinge structure that subjects the current supply conduit to a twisting action that is less objectionable than a relatively acute twist conventional to most hinged arrangements.

Another broad object of the invention is to provide a support for such illuminating means so that various portions of said support and the illuminating means may serve auxiliary purposes.

Other objects and features of the invention will be set forth more fully hereinafter.

The full nature of the invention will be understood from the accompanying drawings and the following description and claims:

In the drawings

Fig. 1 is a front elevation of an attachment adapted for mounting upon the back of a stove and projecting upwardly near the back thereof and above the top plane of such stove.

Fig. 2 is a section taken slightly off-center in Fig. 1 and with the clock embodiment removed.

Fig. 3 is a front elevation with the illuminating means swung to the left and pivoting upon the left hand end.

Fig. 4 is a similar view of the same parts, but swung to the right and pivoting upon the right hand end.

Fig. 5 is a diagrammatic view of a multiple hinge exemplification corresponding to the structure shown in Fig. 3, except that the swingable element is not swung to as great a degree.

Fig. 6 is a view of the parts shown in Fig. 5, but oppositely swung and in this respect corre-

2
sponds to the position of the parts shown in Fig. 4.

Fig. 7 is a front elevational view of a modified form of the invention.

Fig. 8 is a side elevation thereof, the dotted lines indicating alternate positions of the illumination means.

Fig. 9 is a front elevation of another modified form of the invention.

10 In the drawings the invention is illustrated as an attachment. It includes a pair of parallel upwardly directed channel members 10. These may mount brackets 11 if desired. These channels are adapted for suitable anchorage to the back of a stove structure and may secure the base 13 with its lower edge 13a coincident with the top plane of a stove, or with the top edge of the back splasher thereof if desired or required. Also, the members 10 may be so secured as to position the base 13 at any desired elevation.

15 The base 13 is inclined downwardly and forwardly as shown more generally in Fig. 2. It includes a recess or compartment 14, the back of which is provided with knockout portions 15. The front of the recess or compartment may be provided with a hinge closure, not shown, and same could, when desired, constitute an open compartment for the reception of condiment containers for use at the stove.

20 In Fig. 1 this compartment 14 is shown provided with and closed by a clock panel 16, which has the knob 17 and 18 exposed on the face thereof for setting and starting purposes, it being assumed that the clock control 19 is of electrically operable type.

25 It will be noted that one channel 10 is apertured as at 20 and current supply means 21 passes through this channel and into the conduit formed by a complementary closure, not shown, associated therewith, and this current conduit means 21 leads upwardly and has one branch, when an electric clock is employed, adapted to enter the opening formed by knocking out the knockout portion 15. The conduit current means is extended upwardly and is projected forwardly, as indicated at 22, see Figs. 3 and 4.

30 The base 13, as stated is suitably secured to the channels or uprights 10 and upon the upper forward face of said base 13 there is secured a hinge structure generally. This hinge structure includes the support member 23 apertured at 24 to pass the conduit 22. This member 23 has its forwardly projecting flanges 23a and 23b.

35 There is mounted in the base 13 a push button switch 24' that controls current supplied by the conduit 21—22. Extending upwardly from the

right hand end of the member 23 is the member 25 and it has a forwardly directed portion 26. A link 27 has one end pivotally connected thereto as at 28. In axial alignment therewith, but spaced therefrom is pivotally connected at 29 to the lower edge 23b another link 30. The opposite end of the member 23 has secured to it the member 31, which depends and then projects forwardly at 32 providing a pivotal support 33 for another link 34 that lies beneath a rearwardly directed ledge 35 upon a swingable member 36 also having the upper rearwardly directed ledge 37.

This member 36 has the link 27 pivoted at its opposite end to the left hand end of said member 36 as at 38, this pivot being carried by the flange 31. An upper inner link 39 has one end pivotally connected at 40 to the opposite end of the flange 31. The other end of said link 39 is pivotally connected at 41 to the end of the member 23 opposite the previously mentioned ends or adjacent the end to which the member 31 is rigidly connected and this pivot 41 is aligned with the pivot 33. The link 34 is pivotally connected as at 43 to the flange 35 of the swingable member 36 and in axial alignment with the pivot 40. The other end of said link 34, as previously described, is pivoted at 33 upon the depending portion 31.

The other end of the link 30 is connected to the flange 35 at 44, this being at the opposite end of the pivot 43. This pivot 44 is in axial alignment with the pivot 38.

When the right hand end of member 36 is swung outwardly, as shown in Fig. 3, the inside face of member 36 contacts the left hand edge of the member 23 and serves as a stop limiting the movement to slightly more than 90 degrees. In like manner when the member 36 has its left hand end swung outwardly, its right hand end engages the right hand edge of the member 23 and limits this swinging movement to slightly more than 90 degrees. In actual practice this is about 110 degrees.

It will be quite apparent that if the side edges of the member 36 were suitably recessed inwardly immediately above and below the flanges, which are directed rearwardly or inwardly, a greater degree of opening will be permitted. Elongating the central portion of the flange structure 23-23a-23b would also serve to limit the swinging movement at the respective ends thereof.

While herein two series of cooperating links are associated with the two pairs of interfitting flanges, it will be quite obvious that a singular pair of said links will function equally as well in many instances where undue strain is not encountered. It will also be apparent that this type of hinge structure of singular or dual character may be employed in other locations for hinged connecting parts other than those specifically illustrated herein whenever it is desired to have one member swing upon another member from either end thereof, or when it is desired, for example, to form a container, which no matter how positioned, can be opened from one side or the other.

In the specific application, as applied to a stove, it will be recalled that a stove top normally has a support portion at one side thereof, usually about one-half the total area of the stove top, and the other half is devoted to the cooking or heating area.

It is also conventional to mount centrally of the stove directly upon the back or upon the back

splasher or above the same, directly or indirectly, a clock arrangement, as well as a conventional lamp of the character that is operable by a pull cord. This well known canopy and lamp bulb application is quite inefficient for illuminating the interiors of deep vessels and illuminating vessels or objects at a considerable distance from the back of the stove. The present invention, it is obvious, can be used to give equal illumination whether the stove be a right hand type or a left hand type, reference being had to the heating area and the storage area of the stove top. Furthermore, this invention permits the illumination means to be swung outwardly, so as to lie across the top of the stove for illuminating whatever is upon the same. Thus increased illumination efficiency is obtained.

Reference will now be had to the illumination means particularly. To the member 36 there is secured a friction type hinge 50, which hingedly supports a canopy structure 51 that opens downwardly. This friction type hinge is adapted to sustain the canopy in any elevated relation, as shown in Fig. 2, when desired. A pair of partitions 52 is provided therein and said partitions form two end compartments, as shown more particularly in Figs. 3 and 4. Each of said compartments includes a lamp bulb 53 shown dotted in Fig. 2, said bulb being carried by a socket structure, also shown dotted at 54 in Fig. 2, and carried by the partitions. Current wires lead to both bulbs and the back 51a of the canopy is apertured at 55 to pass such current carrying conduit therethrough. The plate member 36 is similarly apertured as at 56 for the current conducting wires.

Now referring more particularly to Figs. 3 and 4, it will be observed that from the aperture 56 the current conductor 51 leads downwardly and thence passes upwardly through an ear 58 at the right hand end of the member 36. It then passes upwardly through another ear 59, these two ears being formed on the ends of a member 60, suitably secured to the rear face 45 of the member 36 near the right hand end thereof.

The member 23 near the left hand end thereof mounts a similar bracket fixture 61 with upper and lower ears 63 and 62, respectively, apertured to pass the current conducting wire portion. The former portion is designated by the numeral 64, the latter by the numeral 65, and these two portions are connected by the intermediate portion 66. The lowermost end of the portion 65, below the apertured ear 62, is extended inwardly as at 67 and connects to the conduit portion 22 at the opening 24 beforementioned. It will be observed, see Fig. 3, that the conduit portion 65 is comparatively elongated and subjected to an axial twist approximately equal to the angular displacement of the swing. In like manner, when the illumination means is swung outwardly from the opposite side, the wire portion 64 is similarly subjected to a corresponding axial twist. This elongated formation subjects this wire to less acute twisting and consequently the wear and breakage thereof incident to swinging of the illumination means is substantially eliminated or materially reduced.

In lieu of a pair of spaced ears a tubular guide may be provided and the same effect obtained therefrom. In other words, there is provided at each end of the structure aforesaid an elongated guide means for insuring elongated axial twisting of the current conducting means.

As shown in Fig. 3, the member 36 has an aperture 68 therein. This also appears in Fig. 4. The rear face 51a is similarly apertured as at 69 and when the canopy is in normally lowered position these two apertures register so that the light bulb in the left hand compartment will show through these registering openings and such light may be used for egg candling purposes either when the illumination means is swung to the left as shown in Fig. 3, or swung to the right as shown in Fig. 4, whichever is most convenient for the housewife.

The central compartment is indicated by the numeral 70 in Fig. 2. Its sidewalls mask or conceal the connections to the light bulb sockets that are mounted in the partition members 52. The interior surface of this compartment may be highly mirrorized so as to constitute a reflecting surface. Hingedly connected as at 73 is a closure 74 for the compartment 70 and this closure may be frictionally retained by friction latches 75 at opposite sides of the compartment. The tip 76 of said closure may serve as a finger piece. The hinge may be of friction locking type if desired.

This compartment may hold a potholder and when the parts are positioned as shown in Fig. 1, thumb pressure upon the finger piece 76 will release the closure 74 and upon dropping of said closure, thereby opening the compartment, the potholder will automatically drop into the hand ready for instant use.

This arrangement also has another possible use. If the inner surface or face of the closure 74 is highly mirrorized, this may serve as a make-up mirror and the compartment 70 may contain the usual cosmetics, applicators and the like. The housewife can, before leaving the kitchen to answer a door alarm, raise the illumination unit upon the hinge 50, press the button 24, thereby energizing both lights, and lower the mirror 74 from the closed position shown in Fig. 2 to either dotted line position shown in said figure. This provides proper illumination for the purpose desired, as well as the mirror for such purpose, and the compartment can, as stated, contain the accessories for such purposes.

It will be also observed that when the canopy structure is in its normal or lowered position, the light bulbs reflect the illumination downwardly and inasmuch as the face of the base 13 is inclined, the face of the clock will be illuminated to a far greater degree than if the face of the base 13 were vertical.

It will be observed that when the mirror member 74 is closed, grease spattering or the like cannot attach thereto. Likewise it has been found that when the interior surfaces are of mirrored character, the heat therefrom is materially reduced, because radiant heat from the stove burners is prevented from passing into the compartment since bright surfaces do not radiate such heat.

Instead of potholders or the like being contained within the compartment 70, certain utensils used about the stove may be contained therein and if the conventional friction hinge be insufficient to retain the closure in its closed position, when the canopy is in its normal position, the latches 75 aforesaid insure positive retention of the closure 74 in the closed position. If desired this may be a positive automatic latch only releasable by finger pressure. Such latches are well known and require, it is believed, no additional illustration or description.

Whenever the recess 14 is not desired for clock mounting, nor for condiment vessel accommodation, this recess is adapted to receive cooking implements, cutlery, etc. Naturally, of course, a closure for said recess 14 may be provided and this may be of the same character as shown for the compartment 70, or of any other desired character.

It is again emphasized that by reason of the 10 inclination of either hinge axis with respect to the top plane of the stove that if the illumination means is swung outwardly from either side, the outer end thereof automatically elevates to an elevation greater than that theretofore occupied by that end when in normal position and such increased elevation permits the housewife to stir within deep vessels on the stove and at the same time adequately illuminates the interiors of the vessels and contents therein.

20 In Fig. 7, 100 indicates the stove proper having the top 101 and the back splasher 102. A pair of depending members 103 is suitably carried by the back of the stove and is extended above the back splasher, as shown by dotted lines, and to 25 the same is secured a central keystone outlined central member or base 104 that herein is shown provided with a clock 105 and associated with which are the starting and setting members 106 and 107. This also carries a light controlling 30 switch 108.

Hingedly connected to the inclined side as at 109 and to each inclined side of said ornamental base is the canopy 110 supporting the socket 111 in which is mounted the light bulb 112. By 35 reason of the inclination of this side, the hinge axis is inclined to the plane of the stove top. By reason thereof, accordingly, when either one of the two canopies are swung out over the top, the outer end of the swung canopy automatically and progressively elevates.

Whenever the support members 103 and the base 104 is inclined upwardly and rearwardly, as shown in Fig. 8, the canopy, when swung over the top, elevates to a still greater degree and it will 45 be observed that this inclination of the base is not objectionable from an aesthetic standpoint.

In Fig. 9 it will be noted that the stove 200 has the top 201 with the back splasher 202. Herein a central member is provided and this, preferably 50 in the manner shown in Fig. 8, is inclined upwardly and rearwardly and near the upper end mounts a light switch 204. A pair of canopies are hingedly connected at 205 and each canopy mounts a socket 206 in which is mounted a light bulb 207. Both bulbs are, naturally, simultaneously controlled by the switch 204 and this also applies to the modification shown in Figs. 7 and 8.

In view of the illustration of the upward and rearward inclination feature in Fig. 8, an end elevation of the stove shown in Fig. 9 is not believed necessary. Likewise, whenever it is desired to have the panel or base 104 coplanar with the back splasher, such arrangement will be perfectly obvious and needs no additional illustration.

Now by reason of the upward and rearward inclination of the base 203, each of the canopies will, when swung over the table top, have the outer end elevate relative to the previous datum plane thereof. It will also be obvious when less swinging is desired that the member 203 in the Fig. 9 modification need not be inclined upwardly and rearwardly. The advantage of having the light directly over the stove for occasional special use can thus be effected. However, as previously 75 stated, when the base 203 is inclined upwardly

and rearwardly in the manner shown in Fig. 8 with reference to the base 104, the advantage of increased elevation in the swinging of the canopy is obtained.

While the invention has been illustrated and described in great detail in the drawings and foregoing description, the same is to be considered as illustrative and not restrictive in character.

The several modifications described herein as well as others which will readily suggest themselves to persons skilled in this art, all are considered to be within the scope of the invention, reference being had to the appended claims.

The invention claimed is:

1. An attachment including in combination a base, means for attaching same to a stove and the like, a support member rigid with the base, a second member normally parallel thereto, two pairs of links, one pair being pivoted at one end to one member end and at their opposite ends to the relatively remote end of the other member, the other pair of links being pivoted at one end to the opposite end of said one member and at their opposite ends to the relatively remote end of the said other member, and illumination means carried by the said one member and swingable outwardly from the said other member at either end thereof and laterally over the stove in opposite directions, said members when parallel having two parallel links pivoted alignments spaced apart approximately the length of the links.

2. An attachment as defined by claim 1 characterized by the illumination means being downwardly directed and the said one member having an opening therein for illumination laterally when said means is swung outwardly in either direction.

3. An attachment as defined by claim 1 wherein hinge means hingedly connects the illumination means to the said one member for illumination means positioning coextensive therewith but angularly thereof.

4. An attachment as defined by claim 1 wherein one end of each member includes means forming an elongated guide coincident with the pivot alignment at that end, and current supply wiring to said illumination means and guided thereby, said wiring effecting relatively approximately a quarter turn between opposite ends of the guided portion when the illumination means is swung on the included axis.

5. An attachment as defined by claim 1 wherein the means for attaching the base is at an angle thereto for relative angular positioning of the support member relative to the plane of the attaching means, either swung end of the illumination means having, when swung, a different elevation relative to a datum plane of said illumination means when unswung.

6. An attachment as defined by claim 1 wherein said illumination means includes a canopy, multiple partitioning therein forming at least three compartments, hinged cover means for an intermediate compartment, a light source at each end of the canopy and in an end compartment, the covered compartment being therebetween, at least one face of the compartment cover means being of mirror character.

7. An attachment as defined by claim 1 wherein said illumination means includes a canopy, multiple partitioning therein forming at least three compartments, hinged cover means for an intermediate compartment, a light source at each end

of the canopy and in an end compartment, the covered compartment being therebetween, at least one face of the compartment cover means being of mirror character, the canopy having hinge connection with said one member for illumination means positioning coextensive therewith but angularly thereof.

8. In combination a pair of parallel members with portions at each end directed towards the other member, a pair of outermost equal length links, cross arranged and pivotally connected at opposite ends to opposite portions at the ends of the members, and an inner pair of similar length links cross arranged and pivotally connected at opposite ends to opposite portions at the ends of the members and reversely of the previous pivoted connections, the several pivoted connections being arranged in two alignments which are parallel and at the ends of said members whereby one member may be swung outwardly relative to the other member and from either end thereof.

9. Structure as defined by claim 8 wherein flexible conduit means is provided and each member at one end supports elongated conduit guide means, the guide means having coaxial alignment with the parallel pivotal axes alignments, said conduit means upon member swinging flexing arcuately substantially proportional to the member swinging.

10. Structure as defined by claim 8 wherein flexible conduit means is provided and each member at one end supports elongated conduit guide means, the guide means having coaxial alignment with the parallel pivotal axes alignments, said conduit means upon member swinging flexing arcuately substantially proportional to the member swinging, each member being apertured intermediate its ends for conduit means passage, said conduit means between passage portions including lengths from the apertures to the guide means, lengths through guide means, and an intermediate portion at least equal to the distance between the spaced guide means.

11. An attachment as defined by claim 1 wherein in the means for attaching the base is at an angle thereto for relative angular positioning of the support member relative to the plane of the attaching means, either swung end of the illumination means having, when swung, a different elevation relative to a datum plane of said illumination means when unswung, said inclined base including a compartment therein.

12. The combination with a stove having a back support and top face and illumination means adjacent the back support and above the plane of the face, of means hingedly connecting the illumination means to the support for swinging the illumination means outwardly and laterally from the support to overlie said face, the hinge axis being inclined to the plane of the face so that the outer end of the swung illumination means is at greater elevation from the face plane than when it is not swung outwardly.

13. The combination with a stove having a back support and top face and illumination means adjacent the back support and above the plane of the face, of means hingedly connecting the illumination means to the support for swinging the illumination means outwardly and laterally from the support to overlie said face, the hinge means including a pair of adjacent links, one being pivotally connected at one end to one end of the back support and at the opposite end to the end of the illumination means most remote

from said back support end, the other link being pivotally connected at one end to the other end of said back support and at the opposite end to the other end of the illumination means.

14. In combination, a supporting member apertured intermediate its ends, a second member apertured intermediate its ends, hinge means adjacent each end of the members for hingedly connecting the second member upon the first member for second member swinging at either end of said supporting member, a plurality of conduit guide means in juxtaposition to the hinge axes and in alignment therewith, and current conducting means extending from the first

5 member aperture and therethrough to one of the axis aligned guide means and therethrough, thence from the upper end thereof to the upper end of another axis aligned guide means and thence from the latter to the aperture of the second member and through same, sagging of the guide to guide defined portion of the current conducting means being of non-interfering character.

10 15. A combination as defined by claim 14 wherein the members are relatively elongated, and at least one of the apertures is positioned near the top of the member so apertured.

JAMES H. REICHART.
